[57] CLAIM

The ornamental design for a combination body scarf and massager, as shown and described.

DESCRIPTION

FIG. 1 is a rear elevational view of a combination body scarf and massager showing my new design;
FIG. 2 is a top plan thereof;
FIG. 3 is a bottom plan view thereof;
FIG. 4 is a left side elevational view thereof;
FIG. 5 is a right side elevational view thereof;
FIG. 6 is a front elevational view thereof; and,
FIG. 7 is a perspective view thereof, with a front pocket in the scarf shown in the open position, and massagers held within the pocket removed from the pocket so as to show their shape.
